CHILD'S BICYCLE

David Sebel, London, England

Application June 10, 1952, Serial No. 20,114
In Great Britain April 10, 1952

Term of patent 14 years

(Cl. D34—15)

To all whom it may concern:

Be it known that I, David Sebel, a subject of the Queen of Great Britain, residing at London, England, have invented a new, original, and ornamental Design for a Child's Bicycle, of which the following is a specification, reference being had to the accompanying drawings forming part thereof.

I claim:

The ornamental design for a child's bicycle, as shown.

DAVID SEBEL.
